LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY

BLOWING DEVICE FOR ROCK DRILLS

Application filed July 23, 1931. Serial No. 552,600.

This invention relates to rock drills, but more particularly to a blowing device for rocks drills of the fluid actuated type.

One object of the invention is to selectively admit pressure fluid under full line pressure and in unrestricted quantities into the drill hole to remove the cuttings therefrom and to simultaneously prevent the delivery of blows against the working implement.

10 Other objects will be in part obvious and in part pointed out hereinafter.

In the accompanying drawing in which similar reference characters refer to similar parts,

15 Figure 1 is a sectional elevation of a percussive tool having the invention applied thereto and showing the position of the parts during the blowing operation,

Figure 2 is a fragmentary view showing 20 the position of the valve holding device during the normal operation of the drill, and

Figure 3 is an elevation in section of a detail taken through Figure 1 on the line 3—3 looking in the direction indicated by the 25 arrows.

Referring more particularly to the drawing, A designates generally a rock drill of the hammer type comprising a cylinder B having a piston chamber C therein to accommodate a reciprocating hammer piston D.

The piston D may be of a well known type having a head E slidable in the piston chamber and controlling a free exhaust port F in the cylinder B. On the front end of 30 the piston D is an integral stem or extension G having a series of flutes H to interlock with ribs J carried by a chuck K which is encased by a front head L.

The chuck K may rotate freely within the 40 front head L and is adapted to receive the shank end of a hollow working implement O, such as a drill steel, which may be suitably interlocked with the chuck in a well known manner to rotate therewith. A front

45 cylinder washer P interposed between the cylinder B and the front head L may extend with its ends into the cylinder and the front head and has a bore Q to serve as a guide for the extension G of the piston.

50 Seated on the rear end of the cylinder B

is an extension R having an end wall S at its front or inner end to serve as a closure for the rear end of the piston chamber C. On the rear end of the wall S is a surface T which acts as a seat for a distributing valve U of the oscillatory plate type arranged in a valve chamber V for which a plate W disposed in the extension R serves as a rearward closure.

The valve U is of a well known type 60 adapted to oscillate or rock from one limiting position to another to control the distribution of pressure fluid from the valve chamber V to the ends of the piston chamber C. The admission of such pressure fluid 65 into the rear end of the piston chamber for actuating the piston D forwardly is conveyed thereto by a rear inlet passage X in the wall S, and a front inlet passage Y formed in the wall S and the cylinder B 70 serves to convey pressure fluid from the valve chamber V to the front end of the piston chamber C for actuating the piston D rearwardly.

The rotation mechanism employed for 75 imparting rotary movement to the chuck K and the working implement O and designated generally by Z comprises the usual rifle bar b which may extend into and interlocking engage the piston D in a well known manner. A ratchet ring c seated on the rear end of the plate W encircles a head d on the rifle bar to act as an abutment for spring pressed pawls e carried by the head d.

80 The admission of pressure fluid into the 85 rock drill for actuating the piston D may be controlled by a suitable throttle valve (not shown) and passes into the valve chamber V through a supply passage f shown, for illustrative purposes, as being located 90 in the extension R.

The rock drill A is further shown as being provided with a tube g which extends coaxially through the drill from the rear end thereof and extends with its front end 95 into the working implement O to convey cleansing fluid thereto for washing the cuttings from the drill hole.

In accordance with the practice of the 100 invention, means are provided for assuring

an uninterrupted supply of pressure fluid to the drill steel whenever the detritus tends to accumulate therein and which, if not expelled from the drill hole, will form 5 a collar of cuttings adjacent the bit end of the drill steel and seriously impede the action of the rotation mechanism. To that end the extension R is provided with a lateral projection h having a bore j, preferably of cylindrical shape, for the accommodation of a U-shaped spring k of which the lowermost leg o is the shorter leg and seats with its edges against the wall of the bore j. 10 Extending through the looped end p of the spring k is a pin q which is seated with its ends in the projection h to prevent endwise movement of the spring k in the direction of the valve chamber V wherewith the 15 inner end of the bore j communicates. 20

The upper leg r of the spring k which is of greater length than the leg o extends into the valve chamber V and terminates at its free end in a hook s which is adapted to 25 seat upon the rear surface of the valve U to press that end of the valve firmly upon the seat T to cover the inlet passage X.

At the juncture of the projection h and the extension R is a bore t which communicates at an intermediate portion with the bore j and has arranged therein a plug u of the rotary type provided with a lever v for its manipulation. In the periphery of the plug u is an annular groove w of a width 30 to accommodate the leg r of the spring k which extends into the groove w and holds the plug u against endwise movement in the bore j. 35

In the side of the plug u and in the same 40 transverse plane as the groove w is a recess x having a flat bottom surface to seat upon the leg r and thus form a wide area of contact between the leg r and the plug when the plug and the leg r are in the positions 45 which they occupy during the normal operation of the drill.

In order to assure a suitable pressure in the rear end of the piston chamber C so 50 that the pressure acting against the front end of the head E of the piston will be unable to actuate the piston into a position to place the front end of the piston chamber C in communication with the atmosphere through the free exhaust port F, the plug u is provided with a passage y which opens at one end into the recess x and communicates at its other end with a bleeder passage z in the extension R and opening into the rear end 55 of the piston chamber C.

A closure may be provided for the outer 60 end of the bore j in the form of a plug 2 which may be secured to the projection h in any suitable manner, as for instance by brazing or welding, as illustrated.

The operation of the device is as follows: Upon the admission of pressure fluid into the valve chamber V, such pressure fluid will normally be distributed by the valve U and flow to the rear and front ends of the 70 piston chamber C through the inlet passages X and Y respectively. The piston D will then reciprocate to deliver its blows against the working implement O and during its reciprocations will place the ends of the piston 75 chamber alternately into communication with the atmosphere through the exhaust port F for exhausting the fluid utilized for actuating the piston.

During this operation of the tool a portion 80 of pressure fluid will flow through the flutes H, thence through the drill steel O into the drill hole during each admission of pressure fluid to the front end of the piston chamber C and will remove the cuttings 85 from the drill hole.

As the depth of the drill hole increases it 90 becomes increasingly difficult to completely remove all the cuttings so that, in consequence, the cuttings will accumulate therein 95 and bring about the unfavorable condition hereinbefore referred to. Whenever it becomes apparent that the alternate puffs of pressure fluid issuing from the front end of the piston chamber C do not suffice to maintain 100 the drill hole free from cuttings the plug u may be rotated to the position illustrated in Figure 1 to depress the leg r of the spring k. The hook s will then seat upon the adjacent end of the valve U to prevent the entrance of pressure fluid from the valve chamber into the inlet passage X.

The opposite end of the valve will then 105 be fully raised and pressure fluid will flow from the valve chamber V through the front inlet passage Y and through the front end of the piston chamber C, thence through the flutes H and the drill steel O into the drill hole to discharge the cuttings therefrom. In the locking position of the plug u the 110 passage y in the plug will register with the passage z and will also be in communication with the valve chamber V, pressure fluid will then flow in restricted quantity, as compared with that flowing through the passage Y, into the rear end of the piston chamber to maintain a suitable pressure 115 therein to balance the pressure acting against the forward area or areas of the piston D.

The plug u will, during this blowing 120 operation, be maintained fixedly in the required position by the leg r which may be slightly flexed at the point whereon the plug u seats to assure a suitable pressure against the plug for holding it immovable.

In tools wherein the piston is provided throughout its length with a bore such as is required to accommodate the rifle bar and the water tube, a pressure balancing that in 130

the front end of the piston chamber may be conveniently maintained in the rear end of the piston chamber since, whenever the pressure rearwardly of the piston approaches a 5 predominating value it will leak through the piston to the drill steel. The pressure in the rear end of the piston chamber will thus be lowered to the same value as that existing in the front end.

10 The blowing device is, however, applicable for use in connection with tools employing solid pistons. When so used the excess of pressure which may accumulate in the rear end of the piston chamber will merely 15 depress the piston D sufficiently to slightly open the exhaust port F, whereupon such excess pressure fluid will escape and the piston D may then immediately return to close the exhaust port F. In tools, however, 20 such as that illustrated wherein pressure fluid may pass through the piston it has been found that the pressure fluid acting against the opposing end areas of the piston will be balanced and that the piston will therefore 25 remain immovable during the blowing operation.

After the drill hole has been thoroughly cleansed the plug u may again be rotated to permit the leg r to move out of the path of 30 the valve U and the leg r, owing to its inherent resiliency, will then press against the bottom of the recess x and maintain the plug u immovable during the subsequent operation of the tool.

35 I claim:

1. A fluid actuated rock drill comprising a casing having a piston chamber and an exhaust port, a hammer piston in the piston chamber controlling the exhaust port and 40 having a blower passage, an automatic valve for distributing pressure fluid to the piston chamber, a spring in the casing, a plug in the casing to actuate the spring against the valve for holding the valve in position to 45 admit pressure fluid into the front end of the piston chamber and to the blower passage, said plug having a groove for engagement with the spring to retain the plug in the casing, a passage in the casing opening 50 into the rear end of the piston chamber, and a passage in the plug to register with the passage in the casing for admitting pressure fluid into the rear end of the piston chamber during the blowing operation to 55 maintain the piston in an intermediate position in the piston chamber for closing the exhaust port.

2. A fluid actuated rock drill comprising a casing having a piston chamber and an 60 exhaust port, a hammer piston in the piston chamber controlling the exhaust port and having a blower passage, an automatic valve for distributing pressure fluid to the piston chamber, a recess in the casing, a 65 U-shaped spring in the recess and having

one leg seated upon the wall of the recess, a plug in the casing to press the other leg of the spring into engagement with the valve for holding said valve in position to supply pressure fluid to the front end of the piston chamber and to the blower passage, said valve having a groove to receive the last said leg of the spring and whereby the plug is retained in the casing, and passages in the plug and the casing to admit pressure fluid into the rear end of the piston chamber during the blowing operation to maintain the piston in an intermediate position in the piston chamber for closing the exhaust port.

In testimony whereof I have signed this 80 specification.
